(57) **CLAIM**

We claim the ornamental design for a pump controller module, as shown and described.

DESCRIPTION

FIG. 1 is an elevated perspective view of the pump controller module of the present claimed invention;

FIG. 2 is a first side view of the pump controller module shown in FIG. 1;

FIG. 3 is a second side view of the pump controller module shown in FIG. 1;

FIG. 4 is a front view of the pump controller module shown in FIG. 1;

FIG. 5 is a top view of the pump controller module shown in FIG. 1;

FIG. 6 is a bottom view of the pump controller module shown in FIG. 1; and,

FIG. 7 is a rear view of the pump controller module shown in FIG. 1.

Features shown in broken lines in the drawings are not part of the claim.
